UNITED STATES PATENT OFFICE.

FRANK MCCLINTOCK, OF WEST UNION, IOWA, ASSIGNOR OF ONE-HALF
TO WM. MCCLINTOCK, OF SAME PLACE.

WIND-ENGINE.

SPECIFICATION forming part of Letters Patent No. 257,880, dated May 16, 1882.

Application filed March 20, 1882 (No model.)

To all whom it may concern:

Be it known that I, FRANK MCCLINTOCK, of West Union, Iowa, have invented a new and useful Improvement in Wind-Engines, of which the following is a specification.

My invention relates to that class of horizontal wind-engines having the sails attached to vertical sail-shafts which revolve in the same direction and with one-half the speed of the engine; and it consists in the manner of gearing the vane and sail-shafts together, so as to dispense with the use of chain-gearing which has been used heretofore. I attain these objects by means of the mechanism illustrated in the accompanying drawings, in which—

Figure 1 is a side view of the engine, showing two arms and sails; and Fig. 2, a top view or plan, showing the construction of the frame-work and the relative positions of the sails to each other and to the vane.

Similar letters refer to similar parts in both views.

The main shaft A, which revolves in journal-boxes bolted to the tower, (only the upper one, B, being shown,) has a casting, C, firmly keyed on its upper end, which forms the hub or center of the frame-work of the engine. The upper part of this casting is hollow, as shown in Fig. 1, in which the side is cut away to show the interior. The arms D, E, F, and G (which I make of iron or other tubing) are attached to the sides of the box C. At the outer extremity of each arm are cast-iron boxes H, having bearings above and below the plane of the frame in which revolve the sail-shafts I. Pieces of tubing L', L², L³, and L⁴ extend diagonally from box to box around the frame, and screw into the sides of the boxes H by right and left hand threads, so that they serve to thoroughly bind together and strengthen the frame-work. A piece of tubing, O, is attached to the cover of the box C, and firmly secured in a vertical position by stay-rods P, extending from the top of it diagonally downward to the arms. A shaft, M, with a vane, N, keyed to its upper end, passes through the tube O, being fitted to journal-boxes at the top and bottom. The sail-shafts I, with the attached sails, are fitted to revolve easily in the bearings in the boxes H, and are geared to the

vane-shaft M by means of bevel-gearing, which I prefer to construct as shown in the drawings. A bevel-gear wheel, a, is keyed on the lower end of the vane-shaft, inside of the box C, with its face upward. Other bevel-gear wheels, b, matching the wheel a, and corresponding in number to the arms of the engine (two being shown in the drawings) gear into the wheel a, and are keyed or fastened with set-screws to horizontal shafts which extend outward through the hollow tubes or arms D, E, F, and G. On the outer end of each of these shafts is another bevel-gear wheel, fastened by set-screws or keys, and inside of the boxes H, and having the same number of teeth as the wheels b. These wheels gear into larger bevel-gear wheels, one of which is fastened by set-screws on each sail-shaft I. These large gear-wheels have the face turned in the opposite direction from the face of the center wheel, a, and have double the number of teeth. The box H on the right-hand arm in Fig. 1 is shown in section, so as to show the arrangement of the gear-wheels, c being the one on the outer end of the horizontal shaft running through the tube D, and d being the one on the sail-shaft.

The sails being set in the correct relative positions with the vane, as shown in Fig. 2, the gear-wheels are all securely fastened, when the action of the wind on the sails will turn the engine. The vane-shaft M and center gear-wheel, a, will be prevented from turning, however, by the force of the wind on the vane N, and the bevel-gearing will cause the sail-shafts to revolve in the same direction as the engine with one-half the speed, and thus keep the plane of the sails in the same relative positions with the vane.

The bevel-gear wheels may be of any convenient size; but the proportion as to number of teeth must be such that the sail-shafts make one revolution while the engine makes two revolutions.

The cap or cover to the central box, C, and sheet-iron covers R to the boxes H, together with the hollow arms D, E, F, and G, through which the shafts pass connecting the gear-wheels b and c, serve to protect the gearing entirely from the weather.

Having thus described my invention, what

I claim as new, and desire to secure by Letters Patent, is—

1. In a horizontal wind-engine, the combination, with a vertical vane-shaft and vertical revolving sail-shafts, of bevel-gearing arranged and operating substantially as and for the purpose specified.

2. In a horizontal wind-engine, the combination, with a vertical vane-shaft and vertical sail-shafts connected by bevel gearing, so that

two revolutions of the engine cause the sail-shafts to make one revolution in the same direction, of covered boxes C and H, and hollow arms D, E, F, and G, for covering and protecting the gearing, substantially as specified.

FRANK McCLINTOCK.
